UNITED STATES PATENT OFFICE.

EDWIN F. ROUSE, OF BAY CITY, MICHIGAN.

CLOTHES-DRIER.

SPECIFICATION forming part of Letters Patent No. 415,285, dated November 19, 1889.

Application filed June 7, 1888. Serial No. 276,331. (No model.)

To all whom it may concern:

Be it known that I, EDWIN F. ROUSE, of Bay City, in the county of Bay, in the State of Michigan, have invented new and useful 5 Improvements in Clothes-Driers, of which the following, taken in connection with the accompanying drawings, is a full, clear, and exact description.

My invention relates to improvements in 10 the class of clothes-driers in which means are provided for folding the drier-arms closely, in order to pack the device for shipment; and my invention consists, essentially, in combining with the standard of the drier a sleeve 15 mounted movable vertically thereon, carrying an arm-bearing collar which turns freely on the sleeve, said collar being provided with supports for the drier-arms and supports for the truss or stay-arms connected to the drier- 20 arms.

It consists, furthermore, in making the aforesaid collar in two separate parts, whereby the arm-carrying collar and stay or truss-carrying collar may be moved independently of 25 each other in order to permit the folding of the drier for the purpose of packing and shipment.

It consists, also, in the detail construction and arrangement of the parts, all as herein- 30 after more fully described, and pointed out in the claims.

In describing my invention reference is had to the accompanying drawings, forming a part of this specification, in which like letters and 35 figures indicate corresponding parts in all the views.

Figure 1 is an elevation of my improved clothes-drier, showing the general construction and arrangement of the parts in position 40 for use. Fig. 2 is a like view illustrating the drier folded in condition for shipment. Fig. 3 is a detached detail of the base of the standard, illustrating the arrangement of the gears for operating the hoisting-drum. Fig. 4 is 45 an enlarged detached sectional view taken on line $x-x$, Fig. 1, illustrating the construction and arrangement of the upper hoisting-pulley and journal-bearing therefor. Fig. 5 is an enlarged section taken on line $y-y$, Fig. 50 1, illustrating the guide-bar of the sleeve mounted on the standard and the device for guiding and securing the hoisting-tackle.

Fig. 6 is an enlarged detached view of the arm-supporting collar, truss or stay arm collar, and the hoisting-arms, illustrating specific features of construction of these parts. 55 Fig. 7 is an enlarged detached view of the sleeve, which is mounted movable vertically on the drier-standard and carries the arm-supporting collar. Fig. 8 is an enlarged vertical section of the supporting-collars for the drier-arms and truss or stay arms, illustrating the specific detail of construction of such parts; and Fig. 9 is an elevation of the drier-standard, of an opposite side thereof to that 60 illustrated in Fig. 1, with a portion thereof broken away for the purpose of showing the construction and arrangement of the means for shaking the drier-arms.

The drier-standard A, which may be of any 70 suitable form or dimensions, is provided with a transverse slot 6, extending from a point above the hoisting-drum to the cap C, or other point sufficiently removed from the hoisting-drum to allow the movement of the drier-arms 75 upon the supporting-standard.

B is the hoisting-drum, which is constructed, preferably, as illustrated in Fig. 1, and is provided with gears 1 and 2, as best shown in Fig. 3, and the handle H, connected with the 80 gears through the medium of a shaft. A pawl and ratchet P, Fig. 1, is employed for the purpose of preventing the unreeling of the drum.

a is a cylinder or sleeve, of metal or other suitable material, of suitable dimensions to fit 85 loosely on the standard A and to slide vertically thereon. The cylinder or sleeve a is provided with a guide bar or lug 3, Figs. 1 and 5, secured near the top of said cylinder, and a guide-bar 10, secured near the bottom 90 of the cylinder a. These guide-bars 3 and 10 fit in the slot 6 of the drier-standard, and serve to guide the cylinder in its vertical movement, without permitting it to turn upon the standard. The guide-bar or lug 3 is connected to the tackle K, and is provided with a hole 4, through which slides the main hoisting-rope I, made of suitable material, which is secured to the cross-bar 10.

Mounted on the cylinder a is the collar E, 100 provided with lugs d, supporting the drier-arms, hinged to which drier-arms are the inner ends of the stay or truss arms S. The cylinder or sleeve a is provided with flanges

or shoulders a' , and the collar E is provided with a groove c' , forming shoulders c^2 , which engage the flange a' of the sleeve a, and the shoulders a' and c^2 serve to retain the collar 5 in place upon the sleeve or cylinder, and also guide the arm-carrying collar as it rotates or turns on the sleeve.

It will be observed on reference to Fig. 8 that the collar E is constructed in two parts, 10 divided at the ledge g, the upper part e being provided with the lug f, serving as a movable support for the inner ends of the stay or truss arms S.

Upon reference to Fig. 7 it will be observed 15 that the cylinder a is divided at a^2 , thus constituting a ledge upon which rests an upper section b, which serves as a carrying-sleeve for the upper section e of the collar E. The upper section e of the collar E is provided 20 with a groove e' , forming shoulders e^2 , which engage the flange or shoulder b' , corresponding with the flange or shoulder a' , which serves to guide and retain the upper collar in its independent movement when the drier is operated in use.

The object or purpose of thus constructing the sleeve a and the arm-carrying collar E is to make an improved drier, so that it may be "knocked down," or folded, for the purpose 30 of close packing in shipment, as well as for the purpose of enabling a person using the same to fold and house the drier, and I accomplish this desirable result by the described construction. At the same time I secure 35 means for carrying the truss or stay arms of the device, which securely brace the drier-arms, thus making the device exceedingly strong and durable, and at the same time providing means for easily adjusting and 40 tightening the cords or wires, which are rove through the drier-arms upon which the clothing or other articles are placed for the purpose of drying the same.

In order to simplify the construction of the 45 drier and at the same time economize in manufacturing the same, I construct the collar E of cast metal, making the patterns in sections, each section being provided with lugs or ears d and f, and casting the sections 50 from such patterns, whereby it is simply necessary to assemble the sections c and e, as shown in the enlarged detached view, Fig. 6. It will be observed that each section c or e is provided with the lug d or f, and when the 55 sections are brought together the drier-arms D and the stay-arms S are journaled between the lugs or against the lugs, and the screw-bolt s securely attaches not only the sections together, but also the drier-arms and stay- 60 arms in their operative positions. The manufacture and construction of the device is thus greatly simplified and the cost thereof considerably reduced, and at the same time the collar is susceptible of embellishment in 65 design for the purpose of adding to the appearance thereof.

The hoisting-rope I is secured to the hub of the lower cross-bar 10 and passes through the hole or opening 4 in the top cross-bar 3 and up through the central enlargement of the slot 6 in the standard A and over the pulley i, journaled on the shaft h. The shaft h is secured to the drier-standard just below the cap C by means of nuts l and n, mounted on the extremities of said shaft or rod and abutting against the drier-standard or an encircling band provided thereon.

When the drier-arms are in position for use, as shown in Fig. 1, the upper section e of the arm-carrying collar E rests normally against the lower section c, the sleeves a and b are in contact with each other, as shown in Figs. 1 and 7, and the flange g' of the upper section e rests on the ledge or shoulder g of the lower section of the collar E; and in this position the drier-arms D are elevated or lowered by simply turning the handle H of the hoisting-drum B.

The folding of the arms D is accomplished by pulling on the lift-cord K, which is secured in the hole 5 of the hub 7 of the upper guide-bar 3, and rove from thence over the small pulley k on the shaft h below the cap C.

The cord or tackle K is independent of the rope I, and after being passed over the pulley k may be passed down through the enlargement of the slot 6 and secured to the outside of the drier-standard, to the opening therein opposite to the hoisting-drum, or, as shown in Fig. 9, through any other suitable opening, and may be secured to a pin or other suitable means on the outside of the drier-standard.

It will be readily seen that when the cord K is pulled the upper part of the section or sections of the arm-bearing collar and the vertically movable sleeve are readily raised, thus elevating the inner ends of the supporting-trusses, and thereby raising the outer ends of the drier-arms and shaking the device.

If desired, it will be understood that a second drum might be provided in the drier, either above or below the hoisting-drum, and the cord or tackle K wound thereon in precisely the same manner as the hoisting-rope I is wound by the drum B; but it is not necessary to illustrate said construction.

In order to take up the slack of the clothes lines or cords L when the drier is folded and packed for shipment, I secure a tie-cord or cords T to the bights of the drier-cords L at the center thereof, and reeve the same with half-hitches over the bight at the center of each drying-cord L, and secure the ends of the tie cord or cords T to pins r, secured to the drier-standard A, as best shown in Fig. 2 of the drawings, thus securing the drier-lines from flapping and becoming entangled with each other when the drier is packed for shipment.

It will be observed that the hoisting-tackle which I preferably employ in my present invention is arranged substantially as in my

application for patent filed December 5, 1887, Serial No. 256,959, excepting that instead of using a hollow standard I substitute the slotted standard A and provide the guide-bar 3, to which the tackle K is secured for shaking the drier, and the guide-bar 10, to which the rope I is secured for elevating the drier-arms, said rope I preferably passing through an opening in the bar 3, which slides independently thereon. This arrangement of the hoisting-tackle, in connection with the loosely-mounted collar and the sleeve a, prevents the hoisting-tackle from becoming entangled or twisted by the rotation of the drier-arms, and leaves the same free to move vertically without friction, while the drier-arms rotate independently on the flange-sleeve a, thus insuring durability of the device and reducing to a minimum the amount of friction necessary for successful operation.

The operation of the drier will be readily understood from the foregoing and upon reference to the drawings.

When the drier is set up for use, the arms 25 may be readily lowered to the height convenient to allow the clothing to be readily placed on the drier-lines L, and when the drier-arms are lowered by turning the handle H, they are elevated by means of the cross-bar 10 and the rope I.

All the parts of my drier are simple in construction, compact and handsome in appearance, and very effective in operation; but it will be understood that considerable change 35 may be made in the detail construction and arrangement of the parts without departing from the spirit of my invention.

Having thus fully described my invention, what I claim as new, and desire to secure by 40 Letters Patent, is—

1. The combination, with the drier-standard of a clothes-drier, of a sleeve mounted movable vertically thereon, an annular flange or shoulder provided on the movable sleeve, 45 between the top and bottom edges thereof, an arm-bearing collar having shoulders on its periphery, between the top and bottom edges thereof, for engaging the flange or shoulder on the movable sleeve, drier-arms connected 50 to the arm-bearing collar, and truss-arms connected to the drier-arms and connected to the standard by a support movable vertically upon the said standard, and means for vertically moving the drier-arms, substantially as 55 and for the purpose set forth.

2. In a knockdown clothes-drier, the combination of the supporting-standard, the sleeves a and b, mounted movable vertically upon the standard, flanges or shoulders a' and b', provided, respectively, on the sleeves a and b with the loose collar c, having the shoulder g, the loose collar e, having the flange g', said collars c and e being mounted, respectively, on the flanges or shoulders a' and b' 65 and engaging the said flanges or shoulders, with shoulders provided on their inside periphery between the top and bottom edges

thereof, and separate hoisting ropes or tackle connected to the separate sleeves a and b to elevate both together or to elevate b independently of a, drier-arms mounted in the collar c, and truss-arms connected to the drier-arms and to the collar e, substantially as and for the purpose set forth. 70

3. The combination, with a clothes-drier 75 standard having a transverse slot through the same, of a vertically-movable sleeve a, having the cross-bar 10, guided in the transverse slot of the drier-standard, and the vertically-movable sleeve b, having the cross-bar 3, also 80 guided in said transverse slot of the drier-standard, loose collars c and e, mounted movably on the sleeves a and b, drier-arms supported in the loose collar c, and truss-arms connected to the drier-arms and to the loose 85 collar e, with hoisting-tackle for elevating the sleeve b independently of a or for elevating both together, substantially as and for the purpose set forth.

4. The combination of the supporting-standard 90 A, provided with the slot 6, a sleeve a, the collar c, having the shoulder g and having the cross-bar 10 riding in the slot 6, the sleeve b, the collar e, having the flange g and having the cross-bar 3 riding in the slot 6, the 95 main hoisting-rope I, secured at one end to the drum B and at the other end to the cross-bar 10 and passing through an opening 4 in the cross-bar 3 and over a suitable guide-pulley i, the rope K, secured to the cross-bar 3, 100 passing over a suitable guide-pulley k to means for operating the same, drier-arms mounted in the collar c, and truss-arms connected to the drier-arms and to the collar e, substantially as and for the purpose set forth. 105

5. The combination of the loose collar e, composed of separate sections removably secured together and having its upper part e detachable from its lower part c, shoulders e², interposed between the top and bottom faces 110 of the part e, and shoulders c², interposed between the top and bottom faces of the part c, drier-arms hinged to the part c, and truss-arms connected to the part e and to the drier-arms, substantially as and for the purpose set 115 forth.

6. The combination of the sleeve b, having the flange b', and the sleeve a, having the flange a', with the sectional collar e, having the groove e' for engaging the flange b' of the 120 sleeve b, the sectional collar c, having the groove c' for engaging the flange a', drier-arms hinged to the collar c, and truss-arms hinged to the drier-arms and to the collar e, substantially as and for the purpose set forth. 125

In testimony whereof I have hereunto signed my name, in the presence of two attesting witnesses, at Syracuse, in the county of Onondaga, in the State of New York, this 28th day of May, 1888.

EDWIN F. ROUSE.
